UNITED STATES PATENT OFFICE

WALTER H. PLEISS, OF LUDINGTON, MICHIGAN, ASSIGNOR TO HANDY THINGS MANUFACTURING COMPANY, OF LUDINGTON, MICHIGAN, A CORPORATION OF MICHIGAN

TOWEL RACK

Application filed May 12, 1930. Serial No. 451,798.

This invention relates to towel racks.

In one well known construction of towel rack, a bracket for attachment to a wall, post or other support is used, and a plurality of rods are disposed one over the other between upper and lower outwardly extending arms of the bracket, and a pivot pin passed through said bracket arms and all of the rods, whereby the rods may be turned independently or individually to different positions with respect to each other and to the bracket.

The rods preferably are of circular form in cross section and the mounting of the same at one end in the manner described is very unsatisfactory. For strength and reinforcement and to maintain the rods against splitting it has been common practice to place a metal ferrule over the ends of the rods which are mounted on the bracket but, as there is only a line contact between adjacent ferrules, any proper mounting of the rods so that they will not become loose or incline downwardly to some extent at an angle to the horizontal is practically impossible while in addition the attachment of the ferrules so as to stay tight thereon is a difficult operation; and any formation of the rods with a flat upper and lower side at the end portions where mounted on the bracket is a matter of expense as the economical way of producing the rods is to form the same in a continuous length, circular in cross section, and cut off at proper lengths for the towel rods, this being a very simple and economical way to produce the same.

The present invention is directed to a novel construction of towel rod mounting where all of the strength and reinforcement of metal parts in conjunction with the ends of the rods which are mounted on the bracket is attained, and at the same time secure engagement of the metal parts with the rods obtained very simply and easily, together with flat bearing surfaces between such metal parts at the ends of the rods where supported to prevent any tilting or sagging. In addition the assembly of the rods and all of the metal members, two of which are used with each rod, so that when the pivot pin is riveted or headed over after passing therethrough a secure, perma-

nent and perfect connection and assembly of the parts is made.

My invention for attaining the objects and results and effects stated is described in the following description, taken in connection with the accompanying drawing, in which,

Fig. 1 is a perspective view of a towel rod made in accordance with my invention.

Fig. 2 is a somewhat enlarged fragmentary side elevation thereof.

Fig. 3 is a vertical section on the plane of line 3—3 of Fig. 2 looking in the direction indicated, and

Fig. 4 is a perspective view of one of the metal parts, two of which are used to embrace the end of each rod where connected with the supporting bracket.

Like reference characters refer to like parts in the different figures of the drawings.

The supporting bracket comprises a back 1 having laterally extending ears 2 through which screws may be passed to secure the bracket to a support. The bracket is made of flat metal and at its upper and lower ends arms 3 are bent forwardly horizontally at right angles to the back 1.

The rods 4, of which any number may be used, depending upon the size of the rods and the distance between the arms 3, are of wood, of a proper and desired length and circular in cross section, the production of which is very economical. With the end of each rod, which is to be located between the arms 3 of the supporting bracket two metal embracing members are used, one at the upper and the other at the lower side of the rod.

Each of these members noted is formed of sheet metal with a flat upper (or lower) side 5 from which flanges 6, one at each edge, are bent at right angles and, in addition, at each end of the side 5 and flanges 6 the metal is drawn into a curved form as indicated at 7 making rounded corners and forming an arc shaped seat at each end of the metal member shaped to fit partly around the curtain rod; so that with one of said members located under and the other over the curtain rod, the arc shaped or substantially semi-circular ends of the metal embracing members may snugly fit or even bite into the surfaces of the rods.

As shown in Fig. 1 three of the rods are located one over the other between the upper and lower bracket arms 3, and each of the rods is equipped with two of the metal embracing members described. Openings are made through the sides 5 of said members, through the arms 3 and through the rods 4, which openings, in vertical alignment, permit the passage of a headed pin 8 which, after it has passed therethrough, is riveted or headed over at its end making a very secure and tight bearing of the flat sides 5 of the metal embracing members against each other and yet spacing all of the rods a short distance vertically from each other. The arms 3 are sufficiently resilient that they may flex or give as much as may be necessary so as to provide a close and tight fitting engagement of the sides 5 of said embracing members with each other and with the lower and upper sides of the upper and lower arms 3 respectively.

It is apparent from the foregoing that a very strong, durable, efficient, practical and economical construction is made. The sheet metal embracing members are stamped in large quantities at very low cost. The supporting bracket is very readily and economically manufactured by use of dies and the assembly is exceptionally quick and easy. When assembled the embracing members engage snugly or bite into the surfaces of the rods, while the flat sides 5 make a relatively wide contact, preventing any loosening or any tilting or sloppy movements of the rods which will always be frictionally retained in any position to which moved. The invention has proved exceptionally satisfactory in all respects. It is defined in the appended claims and is to be considered comprehensive of all forms of structure coming within its scope.

I claim:

1. A device of the class described comprising, a supporting bracket having a vertical back and upper and lower horizontal arms, a plurality of rods located one over the other with one end of each rod between said arms, metal members one over and one under the end portion of each rod located between said bracket arms, said members having horizontal contacting surfaces and formed at their ends with arc shaped recesses for the reception of the rods, and a pin extending through said bracket arms, rods and the members thereon and headed at both ends to permanently secure the parts together and pivotally mount the rods on said bracket.

2. In a construction of the class described, a bracket comprising, a vertical back of flat metal and upper and lower arms bent at right angles thereto to lie in horizontal planes, a plurality of round rods located one over the other with one end of each rod located between said bracket arms, sheet metal members one above and one below the end portion of each rod located between said bracket

arms, said members having flat contacting surfaces and curved on their opposite sides to bear against the rods and a pivot pin extending through said bracket arms, rods and members mounted thereon and headed at both ends to connect the parts securely together in frictional relation to each other.

3. In a construction of the class described, a sheet metal supporting bracket having a vertical back and upper and lower horizontal arms bent therefrom in the same direction, a plurality of rods circular in cross section located one over the other and having each one end thereof located between said bracket arms, two embracing members of sheet metal associated with each rod at the end portion thereof between said bracket arms, one of said embracing members being located above and the other below the rod, and each of said members having channel cross section between its ends and being formed at each end with curved and rounded corners to thereby provide an arc shaped recess at each end of each members to fit the rod, the webs of said channel portions of the members being located in horizontal planes and having bearing contact with the like parts of the adjacent embracing member of the adjacent rod or with the underside of said upper bracket arm and upper side of said lower bracket arm, and a pivot pin passing through said bracket arms, embracing members and rods and headed at both ends to make a permanent and secure connection of the parts together.

4. A metal holding clamp for a wooden rod comprising a flat piece of metal having portions bent at right angles from opposite sides thereof to form flanges, and intermediate portions between the ends of the flanges, said intermediate portions being shaped in conformity with the adjacent periphery of the wooden rod whereby snug engagement may be had therebetween.

In testimony whereof I affix my signature.

WALTER H. PLEISS.
